UNDERWATER AIR CLEANER

Joseph B. Sebok, Detroit, Mich., assignor to
 Houdaille-Hershey Corporation, Detroit, Mich.,
 a corporation of Michigan

Application February 18, 1952, Serial No. 272,154

7 Claims. (Cl. 183—15)

1

This invention relates to improvements in an underwater air cleaner and more particularly to an air cleaner designed for use on military type vehicles, such as jeeps, light trucks, etc., which vehicles frequently travel with the engine and other equipment disposed beneath the hood of the vehicle underwater, although the invention will have other uses and purposes as will be apparent to one skilled in the art.

Liquid bath air cleaners are at present deemed most efficient for cleaning air taken into the carburetor of an internal combustion engine. Many of these devices have been developed in the past, but extreme difficulty has been experienced in endeavoring to provide a liquid bath air cleaner that will satisfactorily operate when submerged. It is not just sufficient to provide an air cleaner that will not leak when disposed beneath the surface of a body of water. It is well known that air is drawn through the cleaner by suction from the internal combustion engine, and this suction inside of the cleaner, plus water pressure at a depth below the surface materially adds to the difficulty of rendering the cleaner water tight. In no instance of which I am aware has a satisfactory underwater cleaner of the liquid bath type been provided heretofore by others.

In addition, devices of this character heretofore made, for open air use, were frequently objectionably expensive in construction, and embodied numerous parts each of which performed their individual function. In the manufacture of air cleaners, especially those for military use, it is essential that the parts be simple in character and as few in number as possible, and for both military and civil use, economy is a highly important factor.

With the foregoing in mind, it is an important object of the instant invention to provide a liquid bath air cleaner in which parts heretofore performing an individual function, are arranged to perform several different functions, thus reducing the necessary number of parts.

Another object of the invention resides in the provision of a liquid bath air cleaner having a 45 spider-like element inside the top of the cleaner which carries the entire filter unit, and the spider element and filter unit are separable when outside the cleaner casing.

Also a feature of the invention resides in the provision of a liquid bath air cleaner incorporating a spider-like element in the upper portion thereof, which single element has a plurality of functions, including the supporting of the filter unit, the sealing of the filter unit against 55 air leakage, holding engagement with the air

2

cleaner casing, and the carrying of unitary means for attaching the filter to the spider element as well as anchoring the cover securing element. In addition the spider member affords an easy hand hold for the removal of itself and the entire filter unit.

A further object of the invention resides in the provision of an air cleaner provided with means adjacent the dirty air inlet to insure proper distribution of the incoming air throughout the cleaner so as to avoid turbulence of the cleansing liquid.

A further object of the invention resides in the provision of a liquid bath air cleaner in which the dirty air inlet is partially baffled to hold in cleansing liquid upon tipping of the vehicle carrying the cleaner.

Also an object of the invention resides in the provision of an underwater liquid bath air cleaner involving means on the filter unit to force the liquid cup into sealing relationship with the casing.

A further feature of the invention resides in the provision of an underwater liquid bath air cleaner which is simple and economical in construction, highly efficient, and which may readily be serviced entirely from the top thereof.

While some of the more salient features, characteristics and advantages of the instant invention have been above pointed out, others will become apparent from the following disclosures, taken in conjunction with the accompanying drawings, in which—

Figure 1 is a top plan view of an air cleaner embodying principles of the instant invention;

Figure 2 is an enlarged vertical sectional view taken substantially as indicated by the line II—II of Fig. 1, looking in the direction of the arrows, this view illustrating the equivalent of a central vertical section through the air cleaner, but showing the section also passing through the air inlet conduit;

Figure 3 is a fragmentary plan view of the air cleaner structure with the cover removed;

Figure 4 is a fragmentary elevational view taken from the left hand side of Fig. 2, to illustrate the inlet conduit and baffle associated therewith; and

Figure 5 is an enlarged fragmentary vertical sectional view illustrating details of construction, this figure being an enlargement of the upper right hand portion of Fig. 2 immediately below the outlet conduit.

As shown on the drawings:

In the illustrated embodiment of the instant invention there is disclosed a casing having a

closed bottom, an open top, and the casing is imperforate as to the side walls with the exception of a suitable opening to accommodate an air inlet conduit 2. While the casing 1 may be fabricated, it is obvious that all joints are made water tight. A cover 3 is provided for the casing, this cover being of substantially dome shape, and having a circumferential gasket holding formation for a gasket 4 which seals the cover in a water tight manner over the upper end of the casing 1, as clearly seen in Fig. 2. Extending through a part of the cover is an outlet conduit 5 for cleaned air.

It will be understood that the inlet conduit 2 will be connected in a water tight manner to an upstanding tube, commonly referred to as a snorkel tube, which will project above the water level even though the vehicle carrying the air cleaner be partially or wholly submerged. It will also be understood that the outlet conduit 5 will be connected in a water tight manner to the air intake of the carburetor associated with the internal combustion engine.

The casing may be provided externally with any suitable form of mounting bracket such as indicated at 6.

Inside the casing, in the lower portion thereof, the casing is shaped to define a gasket holding formation for an annular gasket 7. A cup 8 for cleansing liquid is disposed in the bottom of the casing, and this cup is provided with a reversely turned upper margin 9 for biting and fluid tight engagement with the gasket 7. That establishes a fluid tight seal between the cup and casing bottom, so that in the event the vehicle carrying the cleaner tips or lists to one side, no cleansing liquid from the cup can pass between the cup and the casing bottom and thus be lost for operative use.

As seen clearly in Fig. 2, the cup is inwardly indented as indicated at 10 to provide an inner annular shoulder to be contacted by means later to be described carried by a part of the air cleaner and so forced downwardly to insure a fluid tight engagement with the margin 9 and gasket 7. In the bottom portion thereof, the cup is provided with a suitable handle 11 by means of which it may be lifted out of the casing 1.

Just inside the open end of the casing 1, and partially extending upwardly within the cover 3, is a spider-like retaining plate 12 having a plurality of relatively large apertures 13 in the central dome-like portion thereof. Outward beyond this dome-like portion, the retaining plate is channeled annularly to receive and hold a gasket 14. Outwardly beyond the gasket channel, the plate extends laterally as at 15 and terminates in a circumferential series of relatively wide depressed teeth or projections 16, with relatively wide spaces 17 therebetween, as best seen in Figs. 3 and 5. This plate interlocks with an annular ring 18 secured inside the upper margin of the casing 1. The inner edge of the ring 18 is shaped complementary to the outer edge of the plate, and embodies a plurality of inwardly extending relatively wide teeth or projections 19 separated by open spaces 20 therebetween, each space 20 being of sufficient width to receive therethrough one of the teeth or projections 16 on the plate. One end portion of each of the inward projections 19 on the ring is bent downwardly as indicated at 21 to function as a stop. In connecting these parts, it is a simple expedient to grasp the plate by extending the fingers through the openings 13, inserting the projections 16 of the

plate through the space 20 in the ring, and then turning the plate so as to interlock the projections 16 thereof beneath the projections 19 on the ring, and the turning movement is continued until the projections 16 contact the respective stops 21. The plate is then effectively interlocked in the ring.

Centrally thereof, the retaining plate 12 is fixedly secured to and supports a double nut 22. In the upper end of the nut 22 a thumb bolt 23 extending through a filter unit may be connected, and when this thumb bolt is tightened, the cover is pressed downwardly so that the gasket 4 establishes a water tight seal between the cover and casing 1. Another thumb bolt 24 which extends through a filter unit may be connected in the bottom end of the nut 22, whereby the filter unit is effectively attached to the retaining plate 12 to be supported thereby.

The filter unit includes an open ended shell 25 provided with a bottom 26 having relatively large openings 27 therein, as best seen in Fig. 2. Inside the shell 25 is a mass 28 of filtering material of any suitable character, such for example as wavy wire, curled cattle tail hair, vegetable fiber, etc. A suitable relatively coarse screen 29 may be provided at the top of the filter mass. At the bottom, a baffle 30 is attached to the underside of the bottom 26, the purpose of this baffle being to limit the amount of cleansing liquid carried into the filter mass 28 by air traveling through the cleaner. At the lower corner portion of the shell 25, a plurality (usually three) of spaced feet 31 are provided to bear against the aforesaid shoulder 10 in the liquid cup 8. These feet force the liquid cup downwardly so that the margin 9 thereof effects a positive seal with the gasket 7.

It will be noted that the shell 25, while being concentric with the casing 1, is of much less diameter than the casing 1 so as to leave an air path 32 therebetween leading downwardly toward the liquid sump. Air entering the inlet 2 passes around the shell 25, descends to the curvate shoulder 10 of the liquid cup, and then turns upwardly around the lower end of the shell and passes through the filter mass. In order to prevent incoming air, or a more than desired portion thereof, from immediately descending toward the sump inside the conduit 2, without distributing itself evenly through the air passage 32 entirely around the shell 25, a baffle 33, Figs. 2 and 4, is provided across the lower portion of the air inlet conduit. This baffle not only causes an even distribution of air to prevent turbulence of cleansing liquid, but it also tends to retain the cleansing liquid within the cleaner casing, in the event the vehicle carrying the cleaner tilts or lists sidewise. Without that baffle 33, some cleansing liquid might pass out through the inlet conduit 2 upon a listing of the vehicle, in open air operation.

In operation, air enters the inlet 2, passes over the baffle 33, distributes itself evenly around the path 32, descends toward the liquid sump, passes over the upper face of the baffle and upwardly through the filter mass, and cleaned air exists through the outlet conduit 5. The liquid cup 8 is initially filled with cleansing liquid such as crankcase oil to a depth approximating the indentation 34 seen in Fig. 2.

When the cleaner is serviced, it is a simple expedient to remove the thumb bolt 23, lift the cover off the cleaner, leaving it attached to the conduit from the carburetor. By inserting the

fingers through the opening 13 in the retaining plate, the entire filter unit may then be lifted out of the cleaner. After that, by grasping the handle 11, the liquid cup 8 may be removed from the cleaner. The cup may be emptied of cleansing liquid and accumulated dirt, and replenished with new cleansing liquid. The filter mass need not be serviced as often as the liquid cup, but when it is to be serviced, it may be separated from the retaining plate if desired by the removal of the thumb bolt 24, and swished through kerosene, gasoline, or some other suitable cleansing liquid. In assembling the cleaner for further operation, it is simply necessary to place the refilled oil cup 8 in the casing 1, connect the filter unit with the retaining plate 12, if the same has been removed, thereby forcing the upper margin of the shell 25 in sealing relationship with the gasket 14, place the filter unit in the casing 1, set the cover in position, and tighten the thumb bolt 23. The entire apparatus is then assembled ready for operation, and is completely watertight.

From the foregoing, it is apparent that I have provided an extremely economical and highly efficient air cleaner suitable for underwater usage. Means are provided in the cleaner to insure an even distribution of incoming air so as to avoid turbulence of cleansing liquid. Simple parts of the cleaner are given added function; such for example as the retaining plate 12 which not only supports the filter unit, seals the same against leakage, but also interlocks with the outside casing, and holds means for retaining the filter unit as well as means for anchoring the cover in position on the casing. Further, the entire cleaner is easy to install, and very simple to service.

It will be understood that modifications and variations may be effected without departing from the scope of the novel concepts of the present invention.

I claim as my invention:

1. In an air cleaner, a casing having an open upper mouth end, a removable cover therefor, an apertured retaining plate, cooperative interlocking means on said plate and the mouth of said casing, a filter unit depending from said plate inside said casing, said casing having a closed bottom, an annular gasket in said casing adjacent said bottom, a cleansing liquid cup in said casing having a margin for engagement with said gasket, and projecting feet on said filter unit to contact said cup and force the same into sealing relationship with said gasket.

2. In an air cleaner for underwater service, a casing including a body with a closed bottom and a removable cover, said casing having an inlet and an outlet and being sealed watertight when said cover is in place, sealing means around the wall of the casing inside thereof and above the closed bottom, a cleansing liquid cup in the casing having a turned margin for sealing engagement with said sealing means, an annular shoulder in said cup below said margin, a filter unit in said casing, means supporting said unit, and a plurality of outwardly and downwardly extending feet on said filter unit for engagement with said cup shoulder to maintain the cup margin in sealing engagement with said sealing means.

3. In an air cleaner, a casing assembly having a sump for cleansing liquid in the bottom thereof, a filter unit in said casing assembly open at both ends and of less cross-sectional area than

10 the casing to provide an air path around the unit leading toward said sump, an air inlet conduit connected to said casing, said casing having a single air inlet opening at one side of the casing of substantially the same cross-sectional area as said conduit, baffle means directly blocking the lower portion of said opening to insure an even distribution of incoming air in the path around said unit, and said casing having an outlet for cleaned air on the other side of said filter unit from said inlet.

4. In an air cleaner, a casing assembly having a sump for cleansing liquid in the bottom thereof, a filter unit in said casing assembly open at both ends and of less cross-sectional area than the casing to provide an air path around the unit leading toward said sump, an air inlet conduit connected to said casing, said casing having a single air inlet opening at one side of the casing of substantially the same cross-sectional area as said conduit, a transverse baffle directly over the lower portion of said opening to insure an even distribution of incoming air throughout said path, a cover forming a part of said assembly and sealing said casing watertight, said cover having an outlet opening therein, and means closing the upper portion of said path around said filter unit.

5. In an air cleaner, a casing having an open upper end, a removable cover therefor, a filter unit in said casing, means supporting said unit from the upper end of said casing, an annular gasket holder on the lower part of the inner wall of the casing, a gasket carried by said holder, a cleansing liquid cup in the casing having a margin for engagement with said gasket, and feet projecting from said filter unit to contact said cup and hold the margin thereof in contact with the gasket.

6. In an air cleaner for underwater service, a casing including a body with a closed bottom and a removable cover, said casing having an inlet and an outlet and being sealed watertight when said cover is in place, an annular gasket holding formation on the inside of the casing wall above the closed bottom, a gasket carried by said formation, a cleansing liquid cup in the casing having a marginal portion to rest on said gasket, an annular shoulder in the cup below said margin, a filter unit in the casing, means supporting said unit, and a plurality of outwardly and downwardly projecting feet on the filter unit to contact said shoulder and force the cup margin into engagement with said gasket.

7. In an air cleaner for underwater service, a casing including a body with a closed bottom and a removable cover, said casing having an inlet and an outlet and being sealed watertight when said cover is in place, an annular gasket holding formation on the inside of the casing wall above the closed bottom, a gasket carried by said formation, a cleansing liquid cup in the casing having a marginal portion to rest on said gasket, an annular shoulder in the cup below said margin, a filter unit in the casing, means supporting said unit, and a plurality of outwardly and downwardly projecting feet on the filter unit to contact said shoulder and force the cup margin into engagement with said gasket, said casing having an inlet opening at one side thereof, and a transverse baffle across the lower part of said opening to prevent incoming air making a direct descent toward said liquid cup.

JOSEPH B. SEBOK.
